UNITED STATES PATENT OFFICE.

CLARENCE L. TAYLOR, OF ALLIANCE, OHIO, ASSIGNOR TO THE MORGAN
ENGINEERING COMPANY, OF ALLIANCE, OHIO.

TRAVELING CRANE.

No. 845,380.

Specification of Letters Patent.

Patented Feb. 26, 1907.

Application filed April 27, 1906. Serial No. 314,036.

To all whom it may concern:

Be it known that I, CLARENCE L. TAYLOR, of Alliance, in the county of Stark and State of Ohio, have invented certain new and useful Improvements in Traveling Cranes; and I do hereby declare the following to be a full, clear, and exact description of the invention, such as will enable others skilled in the art to which it appertains to make and use the same.

My invention relates to an improvement in traveling cranes, and more particularly to improvements on the crane shown and described in my application, Serial No. 305,107, filed March 9, 1906.

In my pending application the hoist ropes or chains are suspended from two pairs of drums and pulleys overhanging the sides of the crane and depend outside the main crane-girders.

My present invention consists in main girders, each made up of separated sections, and a trolley having two pairs of drums and intermediate sheaves located in a plane between the separated sections of each girder, whereby the main hoist-chains depend between said separated sections, thus sustaining the load within the outer wheel-bearings of the main trolley.

My invention further consists in providing the bridge with platform on opposite sides of each sectional main girder extending throughout the length of the bridge, thus permitting ready and easy access to the trolley and its mechanism or to the driving-gear of the bridge in the event of a breakdown of any of said parts.

My invention further consists in the parts and combinations of parts and in the details of construction, as will be more fully described, and pointed out in the claims.

In the accompanying drawings, Figure 1 is a view in end elevation of my improved trolley, the traveling bridge being shown in transverse section. Fig. 2 is a view in section on the line A A of Fig. 1; and Figs. 3 and 4 are views in section and side elevation, respectively, of the ladle-bar-carrying devices, the ropes and hoist-drums being shown diagrammatically.

The traveling bridge is adapted to travel on an elevated trackway running lengthwise the mill or foundry. This bridge is composed of the usual end carriages, (not shown,) two sectional main girders on which the main

trolley travels, the sections constituting each girder being parallel and disconnected from end to end, and two parallel intermediate girders on which the auxiliary trolley travels. One main girder is composed of the sections 60 2 and 2^a and the other of sections 3 and 3^a, the four sections constituting the girders being secured at their ends to the end carriages. These sections or girders 2 and 2^a and 3 and 3^a are each preferably made up of I-beams, 65 and each is provided on its top with a rail 5, on which the flanged wheels 6 of the trolley 7 rest and move. The bridge is carried on the trucks 8, two to each end carriage, and each truck is mounted on two flanged track-wheels 9, which travel on the elevated tracks supporting the bridge.

The trolley 7 is provided at its four corners with the compensating-trucks 10, each of which carries two track-wheels 6, arranged 75 side by side, as shown in Fig. 1. These trucks 10 span the spaces between the sections 2 and 2^a and 3 and 3^a and support the main trolley 7 on the four sections of the two girders above referred to. This trolley carries two double drums 15 and 15^a at one side and the double drums 16 and 16^a at the opposite side, the axis of the several drums being parallel with the bridge-girders. Each pair of drums is so located with relation to 85 the sections of the girder on the corresponding side of the bridge that the hoist chains or ropes therefrom pass down between said sections, as clearly shown in Fig. 1. The drums 15 15^a and 16 16^a are all alike, their construction being shown in Fig. 2, and more fully 90 shown and described in my pending application, Serial No. 305,107, filed March 9, 1906.

Each drum is provided, as shown in Fig. 2, centrally with a toothed gear 17, the two 95 gears on the drums of each pair of drums being in mesh, so that a motion imparted to one drum of either pair will transmit motion in the opposite direction to its companion drum. One drum of each pair is connected by gearing with a motor, as fully explained in said application above referred to, so that when the motor is actuated the four drums rotate in unison. Each section of each double inner drum 15 and 16 has a rope or chain 30 secured thereto and adapted to be wound thereon and unwound therefrom. The two ropes or chains from each of the double inner drums 15 and 16 at each end of the trolley 100 pass down between the sections of the main 105 bridge and are wound on the outer drums 15^a and 16^a of the trolley 7. The ropes or chains from the outer drums 15^a and 16^a pass down between the sections of the main 110 bridge and are wound on the inner drums 15 and 16 of the trolley 7.

girders down and around sheaves 31, carried by the frames 31^a, supporting the ends of the ladle-carrying bar 34, while the two ropes or chains from the double outer drums 15^a and 16^a at the opposite ends of the trolley pass down and around sheaves 31, also carried by the frames 31^a. These eight ropes or chains after passing around the sheaves 31 in the frames 31^a, supporting the ladle-carrying bar 34, pass upwardly and around double sheaves 33, which latter are journaled on the trolley at right angles to the axis of the several hoist-drums and in a plane between said drums, as clearly shown in Figs. 1 and 2, and from them down between the sections constituting the main girders, and are secured at their free ends to the ends of the levers 35, pivotally secured in the frames 31^a above the sheaves 31. With this arrangement it will be seen that the ladle-carrying bar 34 is supported by two independent sets of ropes or chains at each end, either set of which will be capable of sustaining the load in the event any one rope or chain should break, thus minimizing the danger due to the breaking of a hoist rope or chain.

Located between the main girders are the intermediate girders 36, having rails on which the auxiliary trolley 37 travels. This trolley carries a drum arranged with its axis at right angles to the direction of travel of the trolley, and its hoist-chain 38 is employed for tilting the ladle or transporting tools and material of any kind.

In order to strengthen the bridge, I connect the sections 2 and 3 of the main girders and the intermediate girders 36 by horizontal and diagonal braces 39 and brace the outer sections 2^a and 3^a of the main girders by the skeleton frames 40, the latter also serving as a support for the platforms 41, which extend throughout the length of the bridge, similar platforms 42 being located between the main and auxiliary girders, as clearly shown in Fig. 1. By means of these platforms the trolley and the bridge driving motor 43, gearing 44, and shaft 45, which are located under one of the platforms, (in the present instance one of the inner platforms 42,) are rendered easy of access in the event of any derangement of parts, and by means of the inner and outer platforms all parts of the main trolley may be reached without danger, and ample room is provided for the examination and repair or removal of any such damaged parts.

It is evident that many slight changes might be resorted to in the relative arrangement of parts shown and described without departing from the spirit and scope of my invention. Hence I would have it understood that I do not wish to restrict myself to the exact construction and arrangement of parts shown and described, but consider myself at liberty to make such slight changes as fairly

fall within the spirit and scope of my invention.

Having fully described my invention, what I claim as new, and desire to secure by Letters Patent, is—

1. The combination of main girders, a trolley thereon, intermediate girders, a trolley thereon, and platform extending the length of the bridge between the main and intermediate girders.

2. The combination of main girders, a trolley thereon, intermediate girders, a trolley thereon, platforms extending lengthwise the bridge between the main and intermediate girders, and platforms located outside of the main girders and extending lengthwise the bridge.

3. A trolley having four drums arranged in pairs, the drums of each pair being parallel and side by side and a pair of sheaves at right angles to and in a plane passing between the drums of each pair.

4. A trolley having four drums arranged in pairs, side by side at opposite sides of the trolley, with their axes parallel with each other and with the bridge, and a pair of sheaves with their axes at right angles to the drums, the sheaves being located in a plane passing between the drums.

5. The combination with a bridge, the main girders of which are composed of separated sections, of a trolley having four drums arranged in pairs, and hoist-ropes depending from each pair between the sections of the main girders.

6. The combination with a bridge the main girders of which are composed of separated sections, and girders intermediate the inner sections of the main girders, of a main trolley mounted on the sectional main girders with its hoist-chains depending between said separated sections, an auxiliary trolley mounted on the intermediate girders, and platforms extending lengthwise the bridge between the main and intermediate girders.

7. The combination with a main trolley having a pair of connected hoist-drums at each end, and a pair of loose sheaves for each pair of drums, the said sheaves being at right angles to the drums and in planes between the adjacent faces of said drums, of hoist-ropes depending from each pair of drums and intermediate sheaves, frames, each carrying sheaves around which the hoist-ropes pass, and a lever to which the free ends of said ropes are secured, and a ladle-carrying bar secured to said frames.

In testimony whereof I have signed this specification in the presence of two subscribing witnesses.

CLARENCE L. TAYLOR.
